UNITED STATES PATENT OFFICE.

PETER J. QUIRK, OF DES MOINES, IOWA.

APPARATUS FOR WEIGHING AND DUMPING COAL.

SPECIFICATION forming part of Letters Patent No. 594,427, dated November 30, 1897.

Application filed June 26, 1897. Serial No. 642,538. (No model.)

To all whom it may concern:

Be it known that I, PETER J. QUIRK, a citizen of the United States, residing at Des Moines, in the county of Polk and State of Iowa, have invented a new and useful Apparatus for Weighing and Dumping Coal, of which the following is a specification.

The object of this invention is to provide an apparatus designed to be placed at the end of a chute leading from a coal-mine or any similar location to receive and contain a quantity of coal as it is dumped from the mine-elevator and to automatically weigh the coal thus received and held and indicate the weight upon a suitable dial, and, further, to provide simple, convenient, and easily-operated means whereby the coal thus held and weighed may be discharged into a car or wagon or the like and then the apparatus be automatically returned to its normal position, ready to receive another quantity of coal.

My invention consists in certain details in the construction, arrangement, and combination of the receiving and weighing device, and also in the construction, arrangement, and combination therewith of the means for discharging the same into a car or wagon, as hereinafter more fully set forth, pointed out in my claims, and illustrated in the accompanying drawings, in which—

Figure 1 shows a side elevation of the complete apparatus with parts of the frame broken away to show certain details of construction and also showing by dotted lines the position in which the apparatus would stand when discharging its contents into a car or wagon, and showing, further, by dotted lines the position of the gate 18 and its hinge 19 when closed. Fig. 2 shows a front elevation of the complete device, shown in its open position ready to discharge into a car or wagon.

Referring to the accompanying drawings, I have used the reference-numeral 10 to indicate the frame of the device. This may be of any ordinary construction and has four uprights at its corners.

The reference-numeral 11 indicates a metal frame supported within the frame 10 upon the springs 12. The frame 11 is designed to support the hopper or receptacle in which the coal is held and which is indicated by the

reference-numeral 13. This hopper has its bottom inclined toward the front at an angle approximating forty-five degrees, so that its contents will freely slide downwardly toward the front when the front is open. At the sides of the frame 11 and hopper 13 are straight-edged tracks 14 and 15. The reference-numeral 16 indicates guides fixed to the frame 10 and designed to receive the tracks 14 and 15, to thereby permit their free vertical movement and limit or prevent any lateral movement. The aforesaid hopper is open at its top, so that coal may be discharged thereinto from a chute, and at the front face of the hopper is a fixed cross-piece 17, and to this cross-piece a gate 18 is connected by means of the hinges 19, so that its lower end may swing outwardly. Pivoted to the lower end portion of this gate 18 at its outer surface are two gravity-latches 20, their outer ends being supported in the brackets 21. In the front edges of the side pieces of the hopper 13 I have provided the notches 22, designed to receive the outer ends of the gravity-latches 20, and so arranged that when the gate 18 is permitted to drop by gravity the said latches will enter the notches 22 and drop behind the shoulders of the said notches and thus securely lock the gate 18. Hence as soon as the gate 18 of the device is released it will automatically drop and lock itself in position to receive and retain a quantity of coal.

The reference-numeral 23 is used to indicate a shaft rotatably mounted in suitable bearings in the frame 10 and having on one or both of its ends an indicator 24. Suitable dials or segmental scales 25 are fixed to the frame 10 in positions where they may be readily seen by the operator of the apparatus and upon which the said dials operate. On the central portion of the shaft 23 is a pinion 26. 27 indicates a rack fixed to the side of the hopper or receptacle 13 and meshed with the pinion 26. By this arrangement it is obvious that when coal is placed in the hopper or receptacle 13 the same will be lowered as the springs 12 are compressed, and this lowering of the hopper or receptacle will obviously cause the rack 27 to rotate the pinion 26, and the indicator 24 will point out upon the dial

or segmental scale the number of tons or fractional parts thereof that are contained within the receptacle or hopper.

I have provided means whereby the contents of the hopper or receptacle 13 may be easily and quickly discharged therefrom and conducted through a suitable chute or trough to a point of discharge—such, for instance, as a car or wagon—as follows:

10 The reference-numeral 28 is used to indicate a chute or trough, which is pivotally connected with the bottom and lower edge of the hopper 13 by means of the hinges 29. Springs 30 are wound upon the pintle of the said hinge, 15 and one end of each spring is made to engage the under surface of the hopper or receptacle and the other the under surface of the said trough or chute to thereby normally hold the trough or chute in an elevated position—that 20 is, parallel with the front face of the hopper or receptacle 13—and this chute or hopper is so arranged that when drawn to its lower limit, as indicated by dotted lines in Fig. 1, it will provide a continued surface with the bottom 25 of the hopper or receptacle and convey the contents of the said hopper or receptacle to a point of discharge at its outer end.

The reference-numerals 31 indicate arms which are attached to the sides of the chute 30 or trough 28 to project at approximately right angles relative thereto, and on the outer ends 35 of said arms are the lugs 32. These arms are arranged in such a position that when the chute or trough 28 is moved from its normal position in a vertical plane downwardly the arms 31 will before the chute reaches its lower position, as indicated by dotted lines at 28, engage the outer ends of the latches 20 and elevate them so that they will pass out of the 40 notches 22. Then the lugs 32 on the said arms 31 will engage the said latches and force the hinged gate 18 outwardly and upwardly, as may also be seen upon reference to the dotted 45 lines in Fig. 1. This of course will permit the contents of the hopper or receptacle 13 to discharge through the chute or trough 28, and when it has thus discharged the operator may 50 release the rope 33, which is attached to an eye 34 on the chute or trough 28, whereupon the springs 30 will operate to move the chute or trough to its upward limit or folded position.

In practical use, assuming that my improved weighing and dumping apparatus 55 were located at the end of the discharge-chute of a mine-elevator, it is obvious that the coal may be taken from the mine and the elevator dumped into the hopper or receptacle of my apparatus the same as is now ordinarily done. 60 An operator may at any time ascertain the exact weight of the coal contained within the hopper or receptacle of the apparatus. When this amount is sufficient for his purpose, all that is necessary is for him to pull upon the 65 rope 33, whereupon the chute or trough 28 is lowered and the contents of the hopper or receptacle automatically discharged there-

from. This is done very quickly, and as soon as the rope 33 is released the device will automatically close and be ready to receive 70 further discharges from the mine-elevator.

Having thus described the construction, arrangement, and function of the various parts of the weighing and dumping apparatus, what I claim as my invention, and desire to secure by Letters Patent of the United States therefor, is—

1. A weighing and dumping apparatus, comprising in combination, a supporting-frame, a hopper or receptacle slidingly mounted therein, and having an inclined bottom, means whereby the said hopper or receptacle is depressed a distance proportionate to the amount of weight contained therein, a gate at the front of the hopper hinged at its upper end so that its lower end may swing outwardly, gravity-latches on the said gate to enter notches in the side of the hopper, a shaft rotatably mounted in the stationary frame, an indicator on the end of the shaft, and a pinion-wheel on its central portion, a segmental scale fixed to the frame in proximity to the indicator, a rack fixed to the hopper or receptacle to mesh with the said pinion-wheel, a trough or chute hinged to the lower corner of the hopper or receptacle, means for normally holding the same elevated, and arms formed on or fixed to the said chute or trough to engage the said gravity-latches and release them when the said chute or trough is pulled downwardly, all arranged and combined substantially in the manner set forth and for the purposes stated. 95

2. A weighing and dumping apparatus, comprising in combination, a frame, a hopper having an inclined bottom slidingly mounted within the said frame, extensible coil-springs fixed to the said frame to support the hopper, guides arranged to permit a free vertical movement of the hopper and to prevent a lateral movement thereof, a gate at the front of the hopper hinged at its upper end so that its lower end may swing outwardly, gravity-latches on the said gate to enter notches in the sides of the hopper, a shaft rotatably mounted in the stationary frame, an indicator on its end and a pinion on its central portion, a segmental scale fixed to the frame in proximity to the indicator, a rack fixed to the hopper or receptacle to mesh with the said pinion, a trough or chute hinged to the lower corner of the hopper or receptacle, springs for normally holding the same elevated, and arms formed on or fixed to the said chute or trough to engage the said gravity-latches and release them when the said chute or trough is pulled downwardly, all arranged and combined substantially in the manner set forth and for the purposes stated. 105 110 115 120 125
